CLAIM

The ornamental design for an animal ear tag, as shown and described.

DESCRIPTION

FIG. 1 is an exploded perspective view of the male and female components of an animal ear tag showing my new design.

FIG. 2 is a right side elevational view thereof showing the male and female components coupled together, the left side being a mirror image of the right side shown;

FIG. 3 is a rear elevational view of FIG. 2;

FIG. 4 is a front elevational view of FIG. 3;

FIG. 5 is a top plan view of FIG. 2; and,

FIG. 6 is a bottom plan view of FIG. 2.

FIG. 5
